UNITED STATES PATENT OFFICE.

CHARLES S. STEVENSON, OF WASHINGTON, DISTRICT OF COLUMBIA.

HAND STAMP.

Application filed October 13, 1922. Serial No. 594,275.

To all whom it may concern:

Be it known that CHARLES S. STEVENSON, a citizen of the United States, residing at Washington, District of Columbia, has invented certain new and useful Improvements in Hand Stamps, of which the following is a specification.

This invention relates to hand stamps or similar hand-operated members, and more particularly to self-righting devices of this kind.

One of the objects of the invention is to provide hand stamps of usual forms with a guard so constructed as to cause it to roll under the influence of gravity to a given position when placed upon a substantially horizontal surface. Another object of the invention is to provide a structure for this purpose which can be economically manufactured and which can be readily applied to existing forms of hand stamps.

Other objects of invention and features of novelty will be apparent from the following specification when taken in connection with the accompanying drawings in which:—

Figs. 1 and 2 are a view in perspective and a plan view, respectively, of one form of the invention as applied to a dating stamp.

Figs. 3 and 4 are a view in perspective and a view in side elevation, respectively, of another form of the invention as applied to a dating stamp.

Fig. 5 is a view in perspective of one member shown in Figs. 3 and 4.

Figs. 6 and 7 are a view in perspective and a view in side elevation, respectively, of another form of the invention as applied to a dating stamp.

Fig. 8 is a view in perspective of one of the members shown in Figs. 6 and 7.

Fig. 9 is a view in perspective of another form of the invention as applied to a hand stamp of a type in common use.

Figs. 10 and 11 are a view in perspective and a plan view, respectively, of another form of the invention, as applied to a hand stamp in common use; and

Fig. 12 is a side elevation showing another modified form of the invention as applied to a hand stamp of the type shown in Figs. 9 to 11.

In the use of hand stamps it is frequently difficult to avoid printing with the type inverted, and the present invention insures that the stamp will always roll to a given

position, though carelessly placed or dropped, so that the user can pick it up and use it without having his attention distracted from his work.

In Figs. 1 and 2, a dating stamp is shown having a top portion 11, with depending side pieces 12 depending therefrom and a lower cross piece 13. A handle 14 is secured to the center of the top portion 11 and the usual type bands 15 are stretched over the lower cross piece 13 and over wheels 16 which are mounted on a pin 17, supported at its ends in the side pieces 12. From the top portion 11, an integral arm 18 extends in a curve downwardly as shown and is terminated at a point adjacent the printing face, and, from that edge of the stamp which corresponds to the lower edge of the type, arms 19^a and 19^b, integral with the side pieces 12, extend in a wide curve, as best shown in Fig. 2, to meet each other at the arm 18 on the other side of the stamp. If desired the arms 19^a and 19^b may be riveted, welded or otherwise secured to each other and to the arm 18 at the point 20. It will also be apparent that, if desired, the arms 19^a and 19^b may take the form of a loop integral with the frame portions 11 and 12 and bent back to the position in which the arms 19^a and 19^b are shown.

When the stamp is placed upon a substantially horizontal surface, it will be supported on one of the lower corners of a side piece 12 and one of the curved arms 18, 19^a or 19^b, or upon the handle 14 and one of the curved arms 19^a or 19^b. In either case the center of gravity of the device as a whole is such that it is in unstable equilibrium in every position except that in which the side of the stamp corresponding to the lower edge of the type rests upon the support, and it will roll quickly to that position from any other position in which it may be placed.

In Figs. 3, 4 and 5, the invention is shown as embodied in arms adapted to be applied to a dating stamp without necessitating any change of form of the stamp. A curved arm 18^c is formed with a bend 18^d for engaging the edge of the top portion 11 of the stamp, and with an extension 18^e provided with an opening 18^f to receive the pin upon which the handle 14 is secured. A curved arm 19^c is reversely bent to provide end-portions 19^d which are formed with openings 19^e so that

it can be mounted upon the pin 17 as shown. It will be apparent that the end portions 19^a may be mounted either outside of the side pieces 12, as shown, or inside such side pieces, and that, if desired, a bolt may be substituted for the pin 17. The arm 19^c may be welded, riveted or otherwise secured to the arm 18^c at the point 20^c, and the extension 18^c may be dispensed with if the 10 arms are rigidly secured to each other.

In Figs. 6, 7 and 8, the invention is shown as embodied in two substantially parallel loops 21 and 22, each having reversely bent end portions 21^a and 22^a and end tabs 21^b 15 and 22^b, which are bent over against the edge of the side pieces 12 of a dating stamp, to hold the loops 21 and 22 rigidly in fixed relation to the stamp. It will be understood that the reversely bent portions 21^a and 22^a 20 are inserted adjacent the inner surface of the side pieces 12 close to the top and bottom thereof, respectively, and the tabs 21^b and 22^b are then bent over to secure the loops in position.

25 The device shown in Figs. 3, 4 and 5 will roll just as will that shown in Figs. 1 and 2, and the curved arms shown in Figs. 6, 7 and 8 will cause the stamp to roll either on a lower corner of a side piece 12 and the 30 lower arm 22, on the handle 14 and the upper arm 21, or on the two arms 21 and 22.

In Fig. 9, the invention is shown as embodied in a single spirally curved arm 23 secured at one end 24 to the front face of a 35 hand stamp of common form, and extending therefrom around the end of the stamp, and spirally and upwardly to a point outside of the plane determined by the corners at the other end of the stamp, and the surface of 40 the handle. As shown, the stamp comprises a body 25, having a type form 26 of rubber or other suitable material, and a handle 27. The lower end of the spiral arm 23 is secured to the front face of the stamp, which 45 corresponds to the lower edge of the type, in any suitable manner, and a weight 28 of lead, or other suitable material is secured to the same face of the stamp to overbalance the weight of the arm 23 so that the stamp 50 will not stand upright in printing position.

In Figs. 10 and 11, the invention is shown as embodied in a stamp somewhat similar to that shown in Fig. 9, and comprising a body 29 with a type form 30 and a handle 31. 55 A single curved arm or loop 32 is secured at its ends to the front face of the stamp, by brads 33 or other suitable means, and extends in an arc around the ends and back of the stamp, in a plane preferably inclined 60 slightly downward from the points at which the loop is secured. A weight 34 is preferably provided to overbalance the weight of the arm 32.

In Fig. 12, another form embodying the 65 invention is shown as applied to a stamp

similar to those shown in Figs. 9 to 11 and having a body 35, a type form 36 and a handle 37. A curved arm or loop 38 is secured at its ends in the same manner as the arm 32 shown in Figs. 10 and 11, but extends in a plane inclined slightly upwardly from the ends of the arm. Another curved arm 39 is riveted, welded or otherwise rigidly secured to the center of the arm 38, or is formed integral therewith, and extends 75 downwardly therefrom to a point adjacent the center of the edge of the type form 36. A weight 40 is preferably provided to overbalance the weight of the arms 38 and 39, and it will be apparent that the arm 39 will 80 function in the same manner as do the arms 18 and 18^c shown in Figs. 1 to 5.

The various curved arms are preferably somewhat resilient to lessen liability of breakage and danger of injuring the surface on which they may be dropped. In all of the embodiments of the invention shown and described, it is apparent that with the curved arms applied to the stamp, the device as a whole will be in unstable 90 equilibrium in every position except one, so that the stamp may be dropped or placed carelessly on a desk or table and will roll to the desired position under the influence of gravity. 95

While a number of embodiments of the invention have been shown and described, it will be understood that changes may be made in the contour and size of the curved arms and in the details of attachment and construction without departing from the spirit of the invention which is defined in the following claims.

What is claimed, is:—

1. An attachment for supporting a hand printing member in rolling relation comprising an arm adapted to be rigidly secured to said hand printing member adjacent one end thereof and extend in a curve about said member to a point adjacent the other end 105 thereof.

2. An attachment for supporting a hand printing member in rolling relation comprising an incomplete loop having a diameter greater than the diagonal extent of the 115 body of said member.

3. An attachment for supporting a hand printing member in rolling relation comprising a partially closed loop having end portions adapted for securing it to the hand 120 printing member.

4. An attachment for supporting a hand printing member in rolling relation comprising a loop adapted to be secured to the printing member, and a curved arm rigid 125 with said loop and extending angularly therefrom.

5. The combination of a hand printing member, and an arm secured to said member and having a curved portion extending 130

partially around and spaced from three sides of the body of said member.

6. The combination of a hand printing member, and a support secured to said printing member and having a supporting edge extending partially about said member in substantially parallel relation to the printing face of said member.

7. The combination of a hand printing member and a curved arm rigidly secured thereto on which said member is adapted to roll under the influence of gravity when placed upon a substantially flat surface.

8. The combination of a hand printing member having a substantially flat face and a curved arm extending about said member from a point adjacent one end of said face to a point adjacent the other end of said face.

20 9. The combination of a hand printing

member and means rigidly secured thereto having a curved surface for supporting said member in unstable equilibrium in every position except one.

10. The combination of a hand printing member and a support secured thereto and having an outer curved edge extending partially around said member in substantially parallel relation to the printing face of said member and an edge extending in a curve from said outer curved edge toward the printing face of said member.

11. The combination of a hand printing member and a support secured at its ends to said member and comprising a loop extending partially about said member and an arm rigid with said loop and extending angularly therefrom.

In testimony whereof I affix my signature.
CHARLES S. STEVENSON.
